UNITED STATES PATENT OFFICE.

JOHN C. GAY, RALPH E. SMITH, AND HARRY J. QUIRK, OF GALION, OHIO, ASSIGNEES
TO THE GALION METALLIC VAULT COMPANY, OF GALION, OHIO, A CORPORATION
OF OHIO.

POWER-DUMP BODY.

Original application filed January 10, 1924, Serial No. 685,332. Divided and this application filed
October 9, 1924. Serial No. 742,535.

Our invention relates to power operated dump bodies, and the present application is a division of our application filed January 10, 1924, Serial No. 685,332.

5 It is the object of our invention to provide a dump body with means which will absorb strains ordinarily imposed on said body and so brace the same that it will not warp out of position; and also with means 10 for eliminating any warping and taking up slack in the absorbing means.

In the accompanying drawings:

Fig. 1 is a plan view of a dump body with the bottom broken away and with some 15 of the braces and supplementary frame members also broken away to show the arrangement of the brace and strain absorbing rods forming the present invention.

Fig. 2 is a side elevation of the complete 20 body and its actuating mechanism mounted on a chassis frame.

Fig. 3 is a detail view showing the manner of fastening one end of each rod to the frame.

25 Fig. 4 is a detail view showing the manner of fastening another end of each rod to the frame and means for adjusting the same.

Referring to the drawings in detail:

30 1 indicates the chassis frame upon which is mounted a supplementary frame 2. U-bolts 3 secure these two frames together. A cross shaft 4 is mounted in the frame 2 and held against lateral movement by pins 5. 35 Pivotally mounted on the shaft 4 are brackets 6 which are attached to the body 7 by bolts 8.

In dump bodies of this character it has 40 been found in practice that strains imposed thereon due to the dumping of heavy loads on uneven surfaces will tend to warp and twist the same. To overcome this defect we have provided means to absorb the strains and strengthen and brace the body and frame to decrease this tendency, and in case the body does become warped we have made provision to eliminate the same and overcome any tendency to further warping. To this end we have provided tie rods 9 and 45 10. The rod 9 is securely fastened to one of the frame members 11, as shown at 12, but any suitable manner of mounting the same may be used. The rod 10 is secured to the

corresponding frame member 13, as shown at 14. As seen in the drawings these rods 55 extend diagonally across the body frame beneath the members 15 and 16 to the front corners of the body proper where they pass through openings 17 in angle irons 18 which are secured to the body 7 in any suitable manner, as by welding. These forward ends of the rods 9 and 10 are screw-threaded and adapted to receive nuts 19 which may be tightened to take up any slack in the rods caused by strains imposed thereon in 60 absorbing strains which would otherwise be imposed on the body and frame and tend to warp or twist the same. Bosses 20 shaped to fit the angle irons 18 are mounted on the tie rods adjacent said angle irons and form 65 70 seats for the clamping nuts 19.

Thus it will be seen that in the use of dump bodies equipped with rods attached to the body frame and to the angle irons secured to the body in the manner described, 75 we are enabled to relieve the body of strains tending to warp and twist the same by absorbing, through the rods 9 and 10, any torque of the body due, for example, to one of the wheels conveying the body dropping 80 into a rut, in which position it must remain during dumping. It will further be seen that any slack in the rods caused by absorbing the strains ordinarily imposed on the body and frame may be taken up by 85 adjusting the nuts 19, thereby materially adding to the life and durability of the truck. It will also be seen that if the body should become warped the adjusting means will serve to overcome such warping. It 90 will also be seen that the rods assist in supporting the bottom of the body and the frame members.

It will be understood that we desire to comprehend within our invention such 95 modifications and changes as may be necessary to adapt it to varying conditions and uses.

Having thus fully described our invention, what we claim as new and desire to 100 secure by Letters Patent of the United States, is:—

In a vehicle, the combination of a body part having angle irons at the forward corners of its bottom, frame members extending longitudinally along the bottom of the 105

body part and spaced inwardly from the sides thereof, tie rods extending diagonally across the bottom of the body part with their forward ends passing through said angle irons and their rear ends passing through intermediate parts of said frame members, and means at the ends of the tie rods for

holding the latter in place, one of the holding means on each rod being adjustable.

In testimony whereof, we affix our signatures.

JOHN C. GAY.
RALPH E. SMITH.
HARRY J. QUIRK.
